Blanchard Chamberlain.

BY Knightford

UNITED STATES PATENT OFFICE.

BLANCHARD CHAMBERLAIN, OF BELLEFONTAINE, OHIO, ASSIGNOR TO
JOSEPH H. WILSON, OF SAME PLACE.

WINDMILL-MOTOR.

SPECIFICATION forming part of Letters Patent No. 252,737, dated January 24, 1882.

Application filed October 15, 1881. (No model.)

To all whom it may concern:

Be it known that I, BLANCHARD CHAMBERLAIN, a citizen of the United States, residing at Bellefontaine, in the county of Logan and State 5 of Ohio, have invented a new and useful Improvement in Windmill-Motors, of which the following is a specification.

My improved device is adapted to be clipped to the vertical pitman or reciprocating rod of a windmill, and to convert the reciprocating motion thereof into continuous rotary motion, while entirely avoiding dead-centers. For this purpose I employ an oscillating yoke having racks on its opposite sides and pivoted at top 15 to the clip which is conveniently fixed to the pump-rod; a pair of pivoted arms being used in connection with the oscillating rack-yokes for guiding the same in its vertical movement and placing its respective racks into gear with 20 the opposite sides of the driving-pinion alternately as said racks are carried up and down.

In order that my invention may be fully understood, it will be explained with reference to the accompanying drawings, in which—

25 Figure 1 is an elevation of a windmill with the invention applied. Fig. 2 is a face view of the guides and pinion on a larger scale. Fig. 3 is a perspective view of the rack-yoke detached. Fig. 4 is a plan or top view of the clip and stud 30 by which the rack-yoke is attached to the pump-rod.

A may represent a wind-wheel of any form or construction mounted on a suitable tower or standard, B, and having on the rear extremity 35 of its shaft C a crank-wheel, D, which runs a reciprocating rod, E, in customary manner.

A suitable pump is shown at F.

G is the oscillating rack-yoke of my improved motor. It is provided on each side with an inwardly-projecting set of cogs or teeth, g g', and at bottom with three studs, h i j.

k is an aperture at top of the yoke by which it is suspended from a stud, l, projecting from the face of the clip L, the arms m m of which 45 receive a clip-plate, N, and nuts n, by which the device is securely fastened to the pump-rod E. The stud l has an aperture near its extremity for the reception of the split key o, to retain the oscillating rack-yoke upon it.

50 P is a plate or standard forming one part of

the stationary frame of my motor. In the said frame are bearings for the pinion-shaft Q, on which are a pinion, R, and a fly-wheel, S.

T T' are a pair of guiding-arms, pivoted on studs t t, respectively, and pressed inward toward the center by springs U U', the inward movement of said arms being arrested by studs v v', the first of which may be near the heel of the arm, while the stud v' is in position to receive the contact of the upper end of the arm 60 T, which is thrown against it.

W represents a central guide consisting of a vertical rib projecting from the face of the plate P.

x is a stud a little on one side of the lower 65 end of the guiding-rib W.

The oscillating yoke is confined to its proper plane of movement by a strap, Y, bolted at its ends to the face of the plate P.

In order to prevent noise, rubber cushions z 70 are placed on the studs v, v', and x, and cushions z' on the faces of the arms T T' where they come in contact with the respective studs.

The operation is as follows: Supposing the parts to be in the position shown in Fig. 1, the 75 pump-rod is now ready to make its upward stroke. At this time the pressure of the guiding-arm T on the stud h throws the bottom of the pivoted yoke to the right, by which means the rack g on the left side is placed in position 80 to gear with the left side of the pinion R and rotate the shaft and fly-wheel in the direction indicated by the arrow. This upward stroke, bringing the right-hand stud j in contact with the guiding-arm T', moves the same to the 85 right, while the pressure thereof holds the central stud, i, in close contact with the right-hand side of the vertical guiding-rib W until the said stud, reaching the top of said rib, is arrested by the upper fixed stud, v', projecting 90 from the plate P. At the same time the pressure exerted by the spring of the pivoted guide-arm T' throws the yoke to the left, bearing the right-hand stud j of the yoke against the side of the fixed stud v'. The upward stroke being now 95 completed, the central stud, i, will be thrust on the left side of the vertical guiding-rib W, firmly bracing the rack-yoke in its left-hand position during the downward stroke, so as to bring the right-hand rack g' in gear with the 100

right side of the pinion R, and continue the rotation of the shaft and fly-wheel in the same direction as indicated by the arrow. During the downward stroke the left-hand stud *h* 5 presses the left-hand spring-arm T sidewise in the manner already described with reference to the right-hand arm until the central stud, *i*, reaches the bottom of the vertical guiding-rib W, when it is thrown sidewise until arrested 10 by the bottom stud, *x*, when the upper stroke is performed as before, a continuous rotary motion being thus imparted to the shaft.

Having thus described my invention, the following is what I claim as new therein and 15 desire to secure by Letters Patent:

1. In combination with the vertical reciprocating rod, the vibrating rack-yoke G, pivoted thereto, and the pivoted guide-arms T T', pressed inward by springs U U', the guide-arms

being intermediate of the springs and rack-yoke, substantially as and for the purposes set forth.

2. The combination, with the vertically-reciprocating rod and the vibrating rack-yoke, of the detachable clip L for pivoting the vibrating rack-yoke to the vertical reciprocating rod, substantially as and for the purposes set forth.

3. The rack-yoke G, formed with cogs *g g'* and studs *h i j*, as set forth.

4. The combination of the vibrating rack-yoke, bearing-plate P, pivoted guide-arms T T', springs U U', central guiding-rib, W, and studs *v v'*, and *x*, substantially as and for the purposes set forth.

BLANCHARD CHAMBERLAIN.
